Inventor:

Henry D. Padget.

By John C. Higdon
Atty.

UNITED STATES PATENT OFFICE.

HENRY D. PADGET, OF ST. LOUIS, MISSOURI.

BRASS AND PACKING GUARD FOR CAR-AXLE BOXES.

1,368,830.

Specification of Letters Patent. Patented Feb. 15, 1921.

Application filed July 30, 1920. Serial No. 400,279.

To all whom it may concern:

Be it known that I, HENRY D. PADGET, a citizen of the United States, residing at the city of St. Louis, State of Missouri, have 5 invented certain new and useful Improvements in Brass and Packing Guards for Car-Axle Boxes, of which the following is a specification containing a full, clear, and exact description, reference being had to the 10 accompanying drawings, forming a part thereof.

My invention consists in the novel construction and combination of parts herein-after particularly described and distinctly 15 claimed.

The object of my invention is to provide a brass protector and packing-guard, or attachment for car axle-boxes, which shall so preserve the packing-material, and which 20 shall be so economical in the use of oil or other lubricant that it will only be necessary to pack the box once each year, instead of every day or oftener, as is necessary with the axle-box constructions heretofore known 25 to me.

Heretofore, the axle-boxes have operated most satisfactorily in hot weather, and have been least efficient in cold weather, because the lubricant is kept warm and thin in hot 30 weather, and so reaches the surfaces of the journals and brasses, while in cold weather the lubricant congeals and fails in many instances to prevent the journal from overheating, cutting and breaking; causing 35 wrecks and damage, to say nothing of loss of life and limb.

A further object of my invention is to provide a brass protector and packing guard which shall prevent accidental lateral 40 placement of the journal and positively lock the packing in the axle-box, and thereby prevent it from being stolen.

Heretofore, car axle-boxes have been 45 robbed by tramps and boys, and the stolen packing has been used to build fires by such persons in cold weather; the packing being cold and gummy crowds its way out of the front of the box and drops upon the ground and is lost; while at other times the packing 50 heaps up against the lid of the box, leaving the journal and brass bare and devoid of any lubrication, with the inevitable result of a "hot" box and possible accident, because of the Babbitt or other soft metal lining melting from the brass bearing and allowing 55 cutting to take place.

After the journal has been worn or cut, as just described, repacking after cooling, has prevented the cut journal from burning completely off, if discovered in time; but in 60 many instances the "hot" box and cut journal have not been discovered in time to prevent a wreck of the train, killing and maiming passengers, if the train be a passenger-train; or, if the train be a freight train 65 carrying oil tank-cars filled with gasoline or other inflammable material, such cars have been blown up by a hot box, causing loss of life, and destroying millions of dollars worth of property, entailing costly damage-suits. 70

In the drawings,

Figure 1 is a fragmentary side-elevation of a truck construction, having my invention applied to the axle-box thereof, the lid of the 75 box being opened up, to show the interior.

Fig. 2 is a plan view of the preferred form of my brass protector and packing-guard, detached from the axle-box.

Fig. 3 is an end-elevation of the guard. 80

Fig. 4 is a side-elevation of the axle-box shown in Fig. 1, with parts in section.

Fig. 5 is a top plan view of a modified, or simplified, form of my packing-guard, detached, and 85

Fig. 6 is a front elevation of said modified form.

The numeral 1 designates the side-frame of the car-truck; 2 the usual axle-box having the customary hinged lid 3 and supported upon the journal 4 of the axle 5 by means of the well-known bearing-brass 6 and wedges 7; and 8 designates one of the car-wheels. 90

The body of my brass protector and 95 packing-guard consists of a flat plate 9 having a series of oil-passages or slits 10 formed in it, and a vertical upstanding integral flange 11 at each end of said plate.

The packing-guard thus formed, is preferably made of metal, and it is fixed within the outer end of the axle-box 2, with said body or flat plate 9 resting upon the body of packing 12 thereat, to hold the latter in place at all times during the operation of 100 the car; there being perforations 14 formed in the said vertical end-flanges 11 of said plate, through which are passed bolts or other fastening-devices 15, to lock said flanges securely to the vertical side-walls of 105 the said axle-box. 110

The said bolts or fastenings 15 have their

bodies passed through apertures formed in the vertical side-walls of said axle-box 2 which register with the perforations 14 of said vertical end-flanges 11 of the guard, and 5 the heads of said bolts are rounded to prevent turning of said bolts from the exterior of said box, the nuts of said bolts being located upon the interior of said box.

Parallel horizontal fingers 16 are secured 10 to, or formed integral with, said flat plate 9 as well as said vertical end-flanges 11.

Said fingers 16 project horizontally from said plate 9 into the spaces in said axle-box which are located between the vertical 15 side-walls of the same and the adjacent journal 4, and thereat bear upon and press downwardly the packing 12 throughout almost the entire length of said journal. The said fingers 16 act as solid abutments, to limit 20 the lateral movement of the said journal 4 in the box; said fingers being made of a body of metal which is practically incom- 25 pressible, so that when the car is jerked back and forth, in switching and coupling operations, the journal is effectually held against accidental displacement, which would otherwise occur, and cause the brass 30 6 to be broken in two and rendered worthless. See Fig. 1.

30 The said oil-passages or slits 10 in the body of the guard, permit oil or other lubri- 35 cant to be supplied to the packing, when desired, without removing the guard.

In axle-boxes that have no room at the 35 side of the journal for the insertion of the fingers 16, the form of guard shown in Figs.

5 and 6 should be used, as that form is de-void of such fingers.

I claim:—

1. A journal-brass and packing protector 40 for car axle-boxes, comprising a flat body of metal from which extends parallel integral solid abutments which fill the spaces at the sides of the journal, and prevent the accidental displacement or breakage of the journal brass by undue lateral movement of 45 said journal; said flat body and said solid abutments resting upon and retaining the packing in said box; in combination with bolts which fasten said solid abutments and 50 said flat body in place upon the interior of said axle-box.

2. A journal-brass and packing protec- 55 tor for car axle-boxes, comprising a flat plate of metal having a series of oil pas- sages in it; a vertical integral perforated flange at each end of said plate; two in- 60 tegral parallel solid metallic abutments pro- jecting from said plate, and adapted to be placed in the spaces between the journal and the side walls of the box, to receive the lateral thrusts of said journal, and prevent the accidental displacement or breakage of the journal-brass; and bolts which pass 65 through the perforations of said flange at each end of said flat plate, and lock the said protector in said axle-box.

HENRY D. PADGET.
